LIMITED-AREA CATHODE

Howard D. Shekels, St. Paul, Minn., assignor to
Radio Corporation of America, a corporation
of Delaware

Application August 16, 1949, Serial No. 110,575

1 Claim. (Cl. 313—346)

1

The present invention relates to an improved gun structure for an electron beam device and to a process for making it. More particularly it relates to an improved gun structure wherein the cathode includes a limited-area or punctiform emission surface supported in exact alignment with an aperture of the control grid and to a process for making it.

As is known, it is desirable for certain electron beam tubes, such as ones used in television for analyzing objects and reconstituting images thereof, that in each tube substantially all of the electrons supplied to its beam should be drawn from a very small and precisely shaped area of its cathode to make it possible to obtain sharp focusing of the beam on the target area.

One way of devising an appropriate gun structure is disclosed in U. S. Patent 2,131,204. According to this patent the cathode is formed with a limited-area emissive surface, i. e., a small mass of emissive material is deposited within a small aperture accurately formed in the center of a non-emissive area of the cathode, which is much larger than the aperture and faces toward the tube target. For example, the small aperture may be formed in the front end of a thimble-shaped outer element of the cathode which serves as a shield and is made of material (such as nickel) having low emissivity. A cathode of this kind is first constructed as a sub-assembly which must then be mounted in the gun so that the small emissive mass is in exact alignment with an aperture in another electrode such as a control grid. If exact alignment is not attained, that other element (the grid) will have a tendency to intercept some of the emitted electrons no matter how precisely the punctiform emission surface may have been formed. This will cause the grid to draw current when it is driven positive, and therefore it will decrease the input impedance which the beam device presents to a circuit for modulating the control grid. In addition, it will distort the cross-sectional shape of the beam by masking the current coming from one side of the accurately-formed emissive portion of the cathode. Yet, in the practical matter of mass producing guns of this type with machines which are only ordinarily precise and with workers who have only average skill, it is almost impossible to obtain exact alignments of the cathodes and grids of the finished guns without tolerating a very high percentage of manufacturing shrinkage.

An alternative practice is known by which it is possible to obtain some of the desirable performance characteristics of guns having limited-

2

area, or punctiform, emission surfaces properly aligned with the control grid aperture. It is to construct the cathode with a relatively large emissive surface and to utilize the grid to mask all of that surface except the portion under the grid aperture so that the aperture will determine the cross-sectional size and shape of the beam. This type of construction does not entail any need for precise alignment of the cathode and control grid in assembling the gun since the emissive surface of the cathode is so large that, no matter how inaccurately these parts may be assembled together, the control grid aperture will register with some part of it.

However, this construction has a number of disadvantages of its own. For one thing, the grid will draw considerable current whenever it is driven positive. This is due to the fact that it will collect electrons from a very large emitting surface, i. e., from all of the emitting surface of the underlying cathode except for the very small portion thereof which lies directly beneath the grid aperture and provides the beam electrons. In addition, the size of the beam cross-section will vary depending upon the potential difference between the grid and the cathode. This is partly due to the combined effect of: (1) the fact that the effective size of the grid aperture varies with its potential (the more negative the grid is the smaller the effective aperture will be); and (2) the fact that in this type of gun the cross-section of the beam is not limited by the size of the emissive area of the cathode. In addition, it is partly due to the further fact that when the grid is near to the cathode potential, or is positive with respect thereto, many of the electrons which pass through the aperture will move with radial components. This will produce on the screen of a picture tube the effect known as "blooming."

For these reasons, in the art of electron beam devices a need has existed for some time for a gun structure in which the cathode has a limited-area, or punctiform, emission surface and in which the emission surface is exactly aligned with the aperture of the control grid independently of the precision with which the cathode and the control grid are assembled together. Besides making it possible to obtain sharp focusing of the beam on the target area, such a structure offers a number of other advantages. Since the emitting area does not have to be limited (electrically) by the grid aperture, that aperture may be made large enough so that the electron optical field aberration, which is pronounced at the edge of the aperture, can be kept away from the

electron beam. Moreover, the use of a large aperture permits the grid-to-cathode spacing to be increased and renders this spacing less critical than usual while at the same time preserving the same control characteristics (beam cut-off and grid bias). In addition if desired this structure permits designs which afford a sharper beam current cut-off, this being a characteristic which is frequently very desirable.

It is an object of the present invention to devise an improved gun structure for an electron beam device wherein the cathode will have a limited-area, or punctiform, emission surface which is in exact alignment with the aperture of the control grid independently of the accuracy with which the cathode and the control grid are assembled together.

It is a further object of the present invention to devise an improved electron gun having a limited-area emission surface which is smaller than the aperture of the control grid and is aligned with said aperture with an exactness which is not dependent upon the accuracy with which the cathode and control grid are assembled together.

It is a further object of the present invention to devise a method for making an improved electron gun whose cathode has a limited-area emission surface including the step of forming the emissive surface on the cathode in exact alignment with the aperture of the control grid without necessitating the use of unusually precise machinery or extraordinary skill.

Other objects, features and advantages of this invention will be apparent to those skilled in the art from the following detailed description of the invention and from the drawing in which:

Fig. 1 represents an electron beam device embodying the improved gun disclosed herein;

Fig. 2 represents a grid-cathode assembly embodying the present invention and illustrates the method of forming its limited-area emission surface according to the present invention; and

Fig. 3 further illustrates the present method for forming a limited-area cathode.

In general, the improved electron gun structure according to the present invention comprises, as its distinctive feature, a grid-cathode sub-assembly including a control grid having a central aperture, a cathode having a non-emissive surface underlying the control grid, and a punctiform emissive coating carried on a limited portion of the non-emissive surface which lies directly beneath the center of the grid aperture and is smaller than the aperture. And, in general, the method for making the gun comprises forming all of the grid-cathode sub-assembly except for the emissive coating and then spraying the coating onto the non-emissive surface of the cathode through the grid aperture while guiding the spray thereto through a duct in a spray-mask which is positioned for properly guiding the spray by being inserted into the aperture itself.

Fig. 1 shows an electron beam device 10 in which I have embodied the improved gun structure disclosed herein. It is a high voltage projection kinescope suitable for a theater television receiving system. Device 10 includes a double-walled envelope 12, this type of construction being particularly advantageous in cathode-ray devices in which the final anode operates at extremely high voltages.

A stream of electrons is provided by a grid-cathode assembly 11, which will be more fully described below and which is enclosed within one

end of the outer neck 13 of the double-walled envelope 12. Assembly 11 is supported partly on cathode tabs, one of which, 15, is shown in Fig. 1, and partly by being combined with other elements of the electron gun of the kinescope to form a unitary structure which has its right-hand end centered in the outer neck 13 by a spacer 17. Adjacent to the grid-cathode assembly 11 there is a second grid electrode 19. It is supported by a number of radially disposed supporting members each of which has its inner end welded to the second grid and its outer end fused into one of a number of elongated glass beads 21 which extend inside and lengthwise of the neck 13. Similar supporting members are used for attaching the grid-cathode assembly to the elongated beads 21. Adjacent to the side of the second grid electrode 19 which faces away from the grid-cathode assembly 11 is a first accelerating anode 24. It is supported in this position by the elongated beads 21 to which it, like other elements described above, is connected by a number of radial supporting elements. The spacer 17 is carried on the first accelerating anode 24 and acts to center it within the inner walls of the neck 13.

The double-walled envelope 12 includes an inner neck 14 having an open end which faces toward the electron-gun end of the tube and is capped with a focusing-electrode 16. The focusing-electrode 16 may be supported by the inner neck 14 in the manner disclosed in co-pending application Serial No. 96,017. The final anode consists of a layer of conductive material 18 which is deposited on the inner surfaces of the inner neck 14 and of the inner side walls of bulb portion of the envelope 12. At one end of the bulb portion there is a relatively flat wall 20, which carries a fluorescent screen 22 on its inside surface.

Fig. 2 shows in detail a suitable form of construction for the grid-cathode assembly 11. This assembly comprises an outer cylinder 30 to the outside of which are attached the radially disposed supporting members for connecting the assembly to the elongated beads 12. At one end of the outer cylinder 30 there is welded a grid-disc 31, which has a very small central aperture 32 which may be of the order of .036" in diameter. Welded around the inner edge of one end of the cylinder 30 directly beneath the grid-disc 31 there is an annular grid-cathode spacer 33 having a shoulder 34 against which a supporting means for the cathode may be made to abut. The spacer 33 serves to fix the distance between the top surface of the cathode and the bottom surface of the grid-disc 31. The supporting means for the cathode is a ceramic spacer 35 formed as a washer, i. e., it has a circular perimeter and a circular perforation concentric therewith. The washer is of such size that it fits closely within the cylinder 30 and its central perforation is of appropriate size to receive a cathode-thimble 36. The cathode-thimble is formed with a pair of shoulders 37 between which the ceramic spacer is held captive. The upper side of the ceramic spacer 35 abuts against the shoulder 34 of the cathode-grid spacer 33 and it is held in this position by a grid shield 38. To this end the shield 38 is welded to the inside of the cylinder 30 and abuts against the lower side of the spacer 35.

A limited-area, or punctiform, emissive coating 39 is deposited on the top surface of the cathode, i. e., on the closed end of the cathode-thimble 36, directly beneath the grid aperture 32. Accord-

ing to the present invention, the coating 39 is formed thereon as disclosed below.

In Fig. 2 a spray mask 40 is shown lifted away from a position of engagement with the grid-cathode assembly 11 in which it is utilized for forming the limited-area coating 39. Fig. 3, on the other hand, shows it in its position of engagement. Spray mask 40 includes a dish-shaped portion 41 and, at the center thereof, a very small neck 42 which has a cylindrical external surface of appropriate size to fit snugly within the aperture 32 and, concentric therewith, an open duct 43 through which emissive material may be sprayed and guided to form the limited-area coating 39. When used for this purpose the spray mask is placed on top of the grid-cathode assembly 11 with the neck 42 extending through the aperture 32.

The spray mask 40 may be formed in any suitable manner. For example, it may be stamped of thin metal so that the structure of the neck 42 consists of an extrusion of a portion thereof at the center of the dish 41. However, it may be turned on a lathe if it is desired to form it more precisely.

In practicing the invention, it will be advantageous to clean out the duct 43 between each use of the spray mask 40, or at least after it has been used for but a limited number of times.

By following this process for applying the emissive coating to the cathode-thimble, the coating will always be in exact alignment with the aperture 32 irrespective of the accuracy with which component parts of the grid-cathode assembly may have been put together. In addition this coating will always be smaller in size than this aperture. Since grid-current is usually drawn only from any portions of the emissive coating of the cathode which may directly underlie the solid part of the grid-disc (and, when the grid is driven quite positive, only from the edges of the portion which lies directly beneath the grid aperture), and since the limited area described herein is smaller than the grid aperture 32, the amount of grid current will never be very substantial during normal operation. Moreover, since the cross-sectional size of the beam will be limited by the small size of the emissive coating 39 rather than by the aperture 32, variations in the potential

applied to the grid will have far less effect upon the thickness of the beam and therefore will act primarily only to intensity-modulate it.

While certain specific embodiments have been illustrated and described, it will be understood that various changes and modifications may be made therein without departing from the spirit and scope of the invention.

What I claim is:

A sub-assembly for an electron gun comprising a cup-shaped grid having an aperture at the center of its closed end to pass electrons, rigidly supported within the grid a thimble-like cathode the closed end of which has a relatively flat non-emissive surface registering with said aperture, a spacer accurately fixing the distance between said non-emissive surface and the under side of said aperture, and a coating of emissive material formed on a central portion of said non-emissive surface beneath said aperture, the coating being of smaller area than the aperture and in exact alignment with it independently of the degree of coaxiality between said grid and cathode.
